BOX SPACING ROLLER AND PRESSER PLATE

James E. Birch, Wolverhampton, England

Application September 14, 1951, Serial No. 246,676

3 Claims. (Cl. 198—34)

1

This invention relates to apparatus for locating crates or boxes while they are on spaced conveyor chains or belts, and has for its object to provide means for accurately locating successively in a predetermined position each crate or box in a moving line, for the purpose, for example, of receiving a load of bottles, jars or like containers from a handling machine or having bottles or the like removed from the crate or box by such a machine. In this connection, a machine with which the locating apparatus constructed according to this invention is adapted for use, is described in our British co-pending patent application No. 19,871 of 1950.

According to the present invention the crates or boxes are carried by spaced parallel conveyor belts or chains, and a roller or abutment, placed transversely of the conveyor belts or chains, is so mounted that it can be moved down between the belts to a level beneath that of the belts, and moved up intermittently to form a stop for each crate or box in turn, so as to hold it in accurate longitudinal relationship relative to a bottle handling machine or the like.

A transversely movable presser member may be provided, which is movable intermittently to engage one side of the crate or box, already located longitudinally by the roller or abutment, and press it against the opposite side wall of the conveyor, or a plate provided thereon, so that the crate or box is positively held and located both longitudinally and transversely.

An embodiment of the invention will now be described with reference to the accompanying drawings, in which—

Fig. 1 is a side elevation of the crate locating apparatus.

Fig. 2 is a plan view of Fig. 1.

Fig. 3 is a schematic diagram illustrating the lay-out and operation of the apparatus.

Referring to the drawings, the crates 10 (Fig. 1), are carried by parallel spaced conveyor chains 11 which run in horizontal guide troughs 12 secured to and supported by cross-members, one of which is shown at 13, connecting the side frames 14 of the conveyor, and one pair of ground engaging supporting legs for the conveyor framework can be seen at 15.

The chain guide troughs 12 support a transverse horizontal axis rod 16 upon which is pivotally mounted a plate 17 having on its upper surface a pair of integral opposed brackets 18, these brackets housing the ends of the axis pin of a roller 19 positioned between the chains 11. Projecting downwardly from the underside of the plate 17 is a lever in the form of a pair of struts 20, which at their lower ends are pivotally connected by a cross-pin 21 to the piston rod 22 of a fluid pressure cylinder 23 which is a single acting

2

cylinder, the piston rod 22 being retracted by an internal spring.

Trunnions 24 on the cylinder 23 engage in bearing holes in brackets 25 depending from a plate 26 secured to the undersides of the chain guide troughs 12, so that the cylinder 23 is mounted for pivotal movement about a transverse horizontal axis. The piston rod is shown in full lines in Fig. 1 in its fully retracted position, in which it will be seen that the plate 17 has been pivoted downwardly upon its axis rod 16 to move the roller 19 downwardly to a position below the level of the conveyor chains 11, so that crates can pass above the roller 19. When pressure fluid is admitted to the cylinder 23 through the conduit 27, the piston rod moves the struts 20 to the position shown in chain lines in Fig. 1, the plate 17 pivoting upwardly about the axis rod 16 and the roller 19 being moved up, to a position above the level of the chains 11, to form a stop for one of the crates 10, as shown in chain lines in Fig. 1.

Pressure fluid will be supplied intermittently to the cylinder 23 at timed intervals synchronized with the speed of the conveyor chains 11, the arrangement being such that after having stopped the first crate 10 of a train, the roller 19 lowers and said first crate commences to move along, above the lowered roller, on the conveyor chains 11, the roller rising again after the transverse centre line of the crate has passed beyond the roller. With this arrangement, as illustrated in Figs. 1 and 3, the roller tilts the crate which is still partly above it, and the next following crate pushes the tilted crate forwards until the said following crate encounters the raised roller 19, the tilted crate having been pushed completely off the raised roller to be carried along by the conveyor chains 11 in the normal way.

A flap or arm member 28 is pivotally mounted upon one side frame 14 of the conveyor frame by means of a horizontal axis pin 29 engaged in lugs 30 provided on the side frame 14. At its upper end the arm 28 has a presser plate 31 secured thereto, whilst at its lower end the arm 28 is pivotally connected with the end of a piston rod 32 of a fluid pressure cylinder 33, disposed transversely to the line of travel of the crates 10. The cylinder 33 is single-acting, the piston rod 32 being spring-returned to its retracted position, and when pressure fluid is supplied to the cylinder 33, through the conduit 34, the piston rod 32 pivots the arm 28 upon the axis pin 29 and the presser plate 31 moves transversely and engages with the side of the crate which has just been stopped by the roller 19, pressing the said crate against a further plate 35 secured to the opposite side frame 14, so that the crate 10 is positively located both longitudinally and transversely.

It will be noted that the cylinder 33 is conveniently pivotally mounted upon a pivot pin 36 in a pair of lugs 37 on one of the depending brackets 25 in which the trunnions 24 of the cylinder 23 are housed.

The timing of the intermittent operation of the cylinder 33 will be such that it moves the presser plate 31 transversely to hold the crate which has just encountered the raised roller 19, and the presser plate is returned to release the crate from this transverse positioning means immediately before or coincident with the lowering of the roller 19.

Fig. 3 illustrates the operation and layout of the apparatus in diagrammatic form, a pressure fluid distributing valve being indicated at 38, which valve 38 is preferably a rotary disc valve, such as is described in our co-pending British application for Patent No. 19,871 of 1950, and will be adapted to control also a bottle handling machine which is filling or emptying the crates 10.

The supply conduit 34 to the cylinder 33 is shown in Fig. 3 as connecting directly with the valve 38, whilst the conduit 27 is shown as incorporating a further individual fluid control valve 39 for controlling supply to the cylinder 23, which valve 39 is operated by a further cylinder 40 connected with the valve 38.

Having fully described my invention, what I claim and desire to secure by Letters Patent is:

1. Apparatus for locating crates, boxes and the like carried by spaced parallel conveyors, comprising a plate member pivotally mounted upon the conveyor framework, a roller mounted upon the plate member, said plate member being pivotal about a horizontal axis and the roller being mounted thereon so that it is positioned transversely between the conveyors, a depending lever on the underside of said plate member, a bracket secured to the conveyor framework, a pressure fluid cylinder pivotally mounted upon said bracket and disposed with its length in the line of travel of the conveyors, the piston rod of said cylinder being pivotally connected with the depending lever, and said cylinder being operated intermittently for pivoting the plate member and raising and lowering the roller from a position in which it is below the level of the conveyors to a position in which it is above the level of the conveyors to form a stop for each crate in turn, a presser arm pivotally mounted upon a side wall of the conveyor for movement transverse to the direction of travel of the conveyors, a second pressure fluid cylinder pivotally mounted upon said bracket and disposed at right angles to the first pressure fluid cylinder, the piston rod of said second cylinder being pivotally connected with the presser arm below the pivotal axis thereof and said cylinder being operated intermittently to cause said arm to engage one side of a crate already located longitudinally by the roller, and a plate secured to the other side wall of the conveyor opposite said presser arm for engaging the other side of the crate, whereby a crate is held and located in the transverse direction.

2. Apparatus for locating crates, boxes and the like, comprising spaced parallel conveyors on which said crates are placed one after the other, means for moving said conveyors, an abutment placed transversely of the parallel conveyors and mounted for vertical movement between said parallel conveyors from one position, in which it is beneath the level of the conveyors, to a second position in which it is above the level of the

conveyors, mechanism for raising said abutment to said second position to engage a first crate above it between the transverse center line and the rear edge thereof to tilt the crate about its forward edge and for maintaining the abutment in said raised position while the next succeeding crate moves said first crate over and off the abutment and engages the abutment and is stopped thereby, mechanism for lowering the abutment to said first position a time interval after engagement by said next crate, means operable in timed relation with the movement of said conveyors to intermittently operate said mechanisms, a presser member mounted for

transverse movement to engage one side of a crate which has been stopped by engagement with said abutment, stop means for engaging the other side of the crate, means for moving said presser member transversely to hold and locate the crate in the transverse direction, a frame member for said conveyor belts, an arm pivotally mounted on said frame member and connected to said presser member, a fluid pressure actuator, and means connecting said actuator and arm.

3. Apparatus for locating crates, boxes and the like, comprising spaced parallel conveyors on which said crates are placed one after the other, means for moving said conveyors, an abutment placed transversely of the parallel conveyors and mounted for vertical movement between said parallel conveyors from one position, in which it is beneath the level of the conveyors, to a second position in which it is above the level of the conveyors, mechanism for raising said abutment to said second position to engage a first crate above it between the transverse center line and the rear edge thereof to tilt the crate about its forward edge and for maintaining the abutment in said raised position while the next succeeding crate moves said first crate over and off the abutment and engages the abutment and is stopped thereby, mechanism for lowering the abutment to said first position a time interval after engagement by said next crate, means operable in timed relation with the movement of said conveyors to intermittently operate said mechanisms, a frame member for said conveyor belts, a plate pivotally mounted on said frame member, means connecting said plate and abutment, a fluid pressure actuator, a lever connecting said actuator and plate to move the latter and abutment upon energization of said actuator, a presser member mounted for transverse movement to engage one side of a crate which has been stopped by engagement with said abutment, stop means for engaging the other side of the crate, means including a fluid pressure actuator for moving said presser member transversely to hold and locate the crate in the transverse direction, and a common mounting bracket for both said actuators.
